UNITED STATES PATENT OFFICE

JULES GASTON DALOZ, OF COURBEVOIE, FRANCE

ELECTRIC MINE LAMP

Application filed June 11, 1926, Serial No. 115,172, and in France June 24, 1925.

This invention relates to electric mine lamps and particularly to those of the type in which the lamp is enclosed in a safety globe containing fluid under pressure.

5 The invention is applicable to all such lamps, but particularly to those of the portable type equipped with batteries.

One of the objects of the invention is to provide a safety globe in which the fluid under pressure need not be constantly supplied as in prior art devices, but in which the pressure fluid is maintained as long as the lamp functions properly or until certain agencies to be described modify its functioning.

Another object is to provide means for maintaining the lamp dimly lighted after pressure fluid has escaped from the safety globe, the degree of incandescence of the filament being modified so that, in the event of breakage of the lamp, there is no danger of explosion of any mine damp that may be present.

A further object is to provide a mine lamp detector in connection with the lamp so arranged that the fluid under pressure in the safety globe escapes in the presence of dangerous gases and either extinguishes the lamp or modifies its luminosity.

30 A still further object is to provide means for charging the lamps with pressure fluid, said means being especially designed to coact with the pressure maintaining device of the safety globe.

35 Other objects will appear in the following detailed description and the drawings in which:—

Fig. 1 is a vertical section of a portable electric mine lamp with a battery, embodying the invention and showing the top portion of the battery and the lamp proper. The safety globe is here shown in its uncharged or discharged position.

40 Fig. 2 is a horizontal section taken on line 2—2 of Fig. 1.

Fig. 3 is a vertical section through another form of lamp especially designed for attachment to a miner's hat. This view shows the safety globe charged with pressure fluid.

45 Referring to Fig. 1 of the drawings, there

is shown a cylindrical shell *a* having an upper threaded portion *a*² adapted to screw into the internally threaded cover member *d* serving as support for the lamp proper. Shell *a* is designed to receive a battery *a*¹ fitted with spring supported terminals *a*³. The lamp proper comprises a safety globe *c* having a terminal annular flange adapted to be clamped between an annular flange formed on cover member *d* and the platform forming the base of the lamp by means of an annular externally threaded member *e*. The globe is clamped between gaskets *f* which serve as cushions between the contacting surfaces on each side of globe *c* and also to hermetically seal the latter. The platform forming the base of the lamp comprises: (1) elements serving to conduct current to and from the lamp; (2) elements for charging the safety globe with gas and for maintaining the gas under pressure therein; and (3) elements forming an elastic switch for diminishing the luminosity of the lamp when gas escapes from the safety globe.

The elements in the lamp base for conducting current to and from the lamp are two contacts *g* imbedded in an insulating disc *b*, a central cylindrical conductor *i*¹ which carries current from one of the contacts *g* to one of terminals of the lamp, and shell *h*, *h*¹ which serves as peripherical support for the lamp and is connected to the second of the two contacts *g* through diaphragm switch *j* and pin *g*¹.

The elements cooperating to maintain the gas pressure in globe *c* and for charging said globe are similar in design to gas valves used for performing the same function in pneumatic tires. There is a valve *i* fitted with a stem which, on being opened, communicates through orifices *h*⁰ and *i*⁰ formed in the lamp supporting members with safety globe *c*. The lamp supporting member *h* is provided with a horizontal extension or flange *h*¹ which is made as large as possible in order to guard against gas leakage. The valve seat for *i* consists of a member having a large upper cylindrical portion, a shoulder, and a lower, partially threaded cylindrical portion *i*¹. The upper cylindrical portion *i*¹

is perforated by hole h^0 and is internally threaded at its upper end to receive an annular threaded member i^4 which serves to clamp metallic cap i^5 in position against the action of spring i^6 . The shoulder of the valve seating member is insulated from h , h^1 by insulating disc i^3 which serves at the same time as, or is combined with a gasket for preventing the escape of gas. The threaded portion of i^2 is in engagement with one of the contacts g , and, by means of nut i^2 , cooperates to hold the whole assembly firmly together. The lower end of i^2 presents a smooth outer surface i^7 adapted to coact with the apparatus for charging the safety globe.

The diaphragm switch comprises an elastic diaphragm j fitted into the lamp base and contacting along its periphery with flange h^1 . The diaphragm is responsive to changes in pressure obtaining in globe c and is deflected against the action of spring j^1 , which tends to oppose said pressure. A threaded pin g^1 carries current from one of the contacts g to the chamber containing the diaphragm j and makes contact with the latter as long as the gaseous pressure is sufficiently high.

In the modification shown in Fig. 3, designed for use with a miner's hat, the above described elements are arranged in a somewhat different manner. The elements serving to conduct current to the lamp, for charging the safety globe and for indicating the release of pressure fluid from said globe, instead of being combined into a unitary structure forming the base of the lamp as in the embodiment shown in Fig. 1, are here distributed between the lamp base and a second structure connected to the latter by proper conduits and wires and forming the cover for the battery shell.

The lamp base, in this modification, comprises an insulating disc m having a perforation therein and carrying a lamp support and a central contact both held in place by screws n forming the terminals for inflowing and outflowing current. The rest of the elements included in the lamp base shown in Fig. 1 are here assembled in the cover structure for the battery receptacle. This cover structure comprises an insulating disc b , a gas charging assembly i , i^1 , i^2 , i^4 , i^7 more or less similar to the one already described, a pair of contacts g on one side of the insulating disc connecting with terminals l on the other side of said disc, a diaphragm switch j , j^1 , g^1 similar to the one described and finally a perforated disc k , which serves the same function as flange h^1 in the modification shown in Fig. 1. The above assembly is held in place in cover member d by an annular externally threaded member e . Cover d is formed with a pair of hollow extensions adapted to receive a pair of flexible tubes p which form a means of gaseous communication between the cover and the lamp and, at the same time, carry

leads o from terminals l to terminals n . The lamp base m forms a wall between a rear chamber of the lamp q^1 , which communicates through the flexible tubes p with the cover d , and a forward chamber q^2 which carries the lamp and serves as a safety globe. The wall of the forward chamber q^2 is formed by an annular shell q which serves as a support for the front glass window, and for the elements for holding the latter in place.

In the construction shown in Figs. 1 and 2, or that shown in Fig. 3, the operation of the apparatus remains the same. In either type of lamp structure, the latter may be charged with gas under pressure in the same manner in which a pneumatic tire is charged and escape of gas from the safety globe, or lowering of the gas pressure from any cause, operates the diaphragm switch to break connection with the battery and to extinguish the lamp.

Either of the above modifications of safety lamps may be employed alone or, they may be equipped with supplemental devices: (1) for detecting mine damp; and (2) for maintaining the lamp dimly lighted after the gas pressure has diminished to any predetermined value. Where the lamp is arranged to remain dimly lighted, its luminosity should be diminished sufficiently to avoid danger of explosive mine gases becoming ignited in the event of breakage of the safety globe and of the lamp proper. The lamp should, however, furnish enough light to indicate its position.

The supplemental structure for maintaining the lamp dimly lighted after partial or total escape of gas from the safety globe is indicated in connection with the form of apparatus shown in Figs. 1 and 3 and includes a spiral resistance wire r interposed between diaphragm j and pin g^1 . The resistance thus arranged is short-circuited when diaphragm j contacts with pin g^1 i. e. when the gas pressure is sufficient to light the lamp. When gas escapes and diaphragm j breaks contact with pin g^1 , current will continue to flow to the lamp through resistance r . The resistance r should preferably be adjusted to give a filament temperature less than 650° C.

The mine damp detector is shown in connection with the form of apparatus illustrated in Figs. 1 and 3 and includes an escape conduit C , preferably in the form of a truncated cone, sealed with some easily fusible substance like wax, A , surrounded with a mass of catalytic material, such as sponge platinum B , located in a chamber, preferably formed by a glass sphere F silvered internally and having a large aperture at its bottom and little holes at its upper part. The latter chamber is preferably packed some such heat insulating material as cotton wadding G which holds the said chamber in position over the mass B . A wire screen H permits entry of

the mine gases into chamber F, these gases being conducted to the said screen by means of the cap D which is suitably formed and connected with the cover member d in consequence.

5 Preferably the whole of the detector is arranged in such a manner that it may be readily changed but only by authorized persons. This may be performed in making said whole 10 detachable when a safety device, such as a magnetic is operated, or by providing lead rivets E³ as shown in the drawing where the chamber F is enclosed in a cap E¹ screwed in an upper extension E of the main cap D, a 15 gasket E² being interposed between flanges of E and E¹.

The manner in which the device operates is as follows: If the lamp is burning in an atmosphere having too high a concentration 20 of mine damp (methane, ethane and the like), these gases will penetrate through screen H and wadding G to sphere F where they will come into contact with the catalyst B. The gases, in coming in contact with the catalyst, will liberate enough heat to melt the fusible seal A. As soon as this seal melts, the gases held in safety globe c will escape through conduit C, thus releasing the pressure 25 on diaphragm j and immediately reducing the luminosity of the lamp. The gas in globe c is preferably carbon dioxide, which, as is well known, is non-inflammable and which when used in the present connection serves to prevent all danger risks. Wire 30 screen H prevents the possible spread of flame from sphere F to the atmosphere outside the lamp.

It is to be understood that the apparatus may be made up with or without the mine 35 damp detector or the dimming attachment and that other charging apparatus may be used in connection therewith than that herein shown and described.

Similarly other sources of current than a 40 battery may be utilized for supplying the lamp or lamps, as for example terminals connected to wires leading to a prime mover situated remotely from said lamp or lamps.

Furthermore, the parts of the invention 45 concerning respectively the dimming means, the detector and the wires surrounded by conduits for fluid under pressure may be utilized on other lamps with a security device under control of a fluid under pressure, all this 55 without departing from the spirit of the invention.

What I claim is:—

1. An apparatus of the class described comprising in combination a source of current, 50 a lamp, a chamber enclosing said lamp, means for sealing a fluid in the space between the lamp and the walls of said chamber, a flexible diaphragm communicating with said space, said diaphragm being connected to one 55 terminal of the lamp socket, a contact lead-

ing to the current source, and a resistance wire connecting said diaphragm to said contact, the diaphragm, the contact and the resistance wire being arranged so that, under pressure the diaphragm flexes against the contact and current flows directly from diaphragm to contact, and, on release of pressure, the diaphragm moves away from said contact and current flows from diaphragm to contact through the resistance wire. 70

2. An apparatus of the class described comprising in combination a source of current, a lamp, a chamber enclosing said lamp; means for admitting pressure fluid into the space between the walls of said chamber and the lamp, a pressure sensitive switch communicating with said space, and means operable by combustible gases to release the pressure on said switch. 75

80 3. An apparatus of the class described comprising in combination a source of current, a lamp, a chamber enclosing said lamp, means for admitting pressure fluid into the space between the lamp and the walls of said chambers, means for modifying the flow of energy 85 to the lamp with change of pressure in said space and means operable by combustible gases to release the pressure fluid from said space. 90

95 4. An apparatus of the class described comprising in combination a source of current, a lamp, a chamber enclosing said lamp, means for admitting pressure fluid into the space between said lamp and said walls of said chamber, means for modifying the supply of energy to the lamp with change of pressure in said space, a pressure fluid outlet tube 100 communicating with said space and sealing means for said outlet tube comprising a substance whose temperature is modified in the presence of combustible gases and a substance of low melting point. 105

110 5. An apparatus of the class described comprising a first unit including a lamp, an enclosing chamber for said lamp, a base for supporting said lamp, said base carrying the lamp terminals and having an orifice therein; a second unit including a cover member, a disc hermetically closing the bottom of said cover member, said disc comprising means 115 for carrying current therethrough, means for passing gases therethrough, means for modifying the flow of current therethrough; and a flexible hose enclosing electrical connections leading from the first unit to the second unit. 120

125 6. An apparatus of the class described comprising in combination a source of current, a lamp, a globe covering said lamp, means for admitting pressure fluid into the space between said lamp and said globe, means for modifying the supply of energy to the lamp with change of pressure in said space, a pressure fluid outlet tube communicating with said space, and sealing means for said outlet 130

tube comprising a metal of the platinum group and a substance of sufficiently low melting point to liquefy under the action of the heat given off by contact of combustible mine gases with said metal.

7. An apparatus of the class defined comprising in combination a chamber adapted to contain a fluid under pressure, means for maintaining a fluid under pressure in said chamber, pressure indicating means adapted to indicate changes of pressure in said chamber, and means operable by a combustible mine gas to release fluid under pressure in said chamber and to thereby actuate said pressure indicating means.

In testimony whereof I hereunto affix my signature.
